UNITED STATES PATENT OFFICE.

LAFAYETTE B. BAILEY, OF YOLYN, WEST VIRGINIA.

COMBINATION TRACK-BOND AND TIE.

1,232,645.

Specification of Letters Patent. Patented July 10, 1917.

Application filed February 5, 1917. Serial No. 146,775.

To all whom it may concern:

Be it known that I, LAFAYETTE B. BAILEY, a citizen of the United States, residing at Yolyn, in the county of Logan and State of West Virginia, have invented certain new and useful Improvements in Combination Track-Bonds and Ties, of which the following is a specification, reference being had to the accompanying drawings.

- 10 This invention relates to railway tracks and particularly to mining tracks and specifically the invention relates to the ties upon which the rails are mounted and to the means for clamping the rails upon the ties.
- 15 One object of the invention is to provide a very simple and very cheap tie and rail bond so constructed that the rails will be held firmly in engagement with the ties and further so constructed that the ties act as 20 bonds electrically connecting the rails.

A further object is to provide a rail supporting structure of the character described wherein the rail clamp is urged toward the rail as it is drawn downward toward the tie 25 thus securing not only a firm engagement of the rail with the tie but a very good electrical connection between the clamp and the rail and the rail and the metallic tie.

Other objects will appear in the course of 30 the following description.

The invention is illustrated in the accompanying drawings, in which

Figure 1 is an edge elevation of a tie and rail bond constructed in accordance with my 35 invention, the rails being shown in section;

Fig. 2 is an enlarged view of one end of the tie and rail clamp, the rail being shown in section and a portion of the tie and clamp being in section;

40 Fig. 3 is a top plan view of the structure shown in Fig. 2, the web of the rail being in section;

Fig. 4 is an under side plan view of the construction shown in Fig. 2.

45 My combined tie and rail bond is especially adapted for coal mines where it is necessary to have a bonded track so that the track will form one side of an electric circuit, one of the objects of the invention being to 50 do away with the use of the ordinary track bonds or rail bonds and substitute therefor my combination track bond and tie. As illustrated in the drawings, my invention comprises a tie 10 preferably formed of a 55 transversely extending metallic bar, the ends of this bar being bent upward and then in-

ward and then upward as at 11 to form relatively fixed rail engaging clamps or abutments which will extend upward on the web of the rail sufficiently to thoroughly 60 brace it against lateral thrusts. The tie, inward of the rail seat 12, is formed with the slots 13. Each of these slots has a vertical inner end and a downwardly and outwardly inclined opposite end 14.

Coacting with the tie are the adjustable rail engaging clamps 15. Each of these clamps has a base portion 16 designed to rest upon the upper face of the tie and an upwardly extending portion 17 designed to 70 engage over the base flange of the rail and engage against the web of the rail. Each of these clamps 15 is longitudinally slotted as at 18 for the reception of a square-shank bolt 19 which extends downward through 75 the base of the clamp and through the tie. Each clamp 15 is also formed on its under side with a downwardly extending lug 20, this lug having its outer face beveled as at 21 to engage with the beveled face 14 of the 80 corresponding slot 13. With this construction it is obvious that as the nut on the bolt 19 is turned up, the corresponding rail clamp 15 will be drawn downward and as it moves downward the beveled face 21 will engage 85 with the beveled face 14 and the clamp will be wedged laterally toward the rail. Thus the rail engaging member or clamp 15 will be not only drawn downward on the rail so as to hold the rail securely to the tie but 90 will also be forced laterally so as to shift the rail over into fixed clamping engagement with the clamping member 11.

All of the parts above described are metallic and, therefore, may be cheaply made 95 and are relatively light. This tie and bond is particularly adapted for mines because the rails are supported only a minimum distance above the floor of the tunnel. Where the height of mine tunnels is limited, as they usually are, this is a considerable advantage inasmuch as under the same conditions a car, motor or mule could be three to four and one-half inches higher (and yet be worked under the low roof) with my construction than with the usual manner of mounting or supporting the rails on the track. Furthermore my construction makes a very rigid track, the rails are held against spreading and yet may be readily detached 100 from the ties at any time for repair or replacement. Furthermore the bolt used with 105

the ties would carry a nut of the same size as the nuts and bolts used on the fish plates so that only one wrench would be necessary in order to construct the track or repair it.

5 It will be seen that in my construction the tie and rail clamp have only three very simple parts. These are very easy and cheap to manufacture. Furthermore my construction uses no keys or lock devices and the nuts 10 may be readily held in place by suitable nut locks against any accidental detachment.

The complete tie would weigh from nine to ten pounds and acts to form a complete electrical bond between the rails of the 15 track, that is from one rail to the opposite rail. Both rails are intended to be connected to the sources of energy so that when the mine car with its motor passes over the rails a return circuit will be provided 20 from the rails through the motor and back to the source of energy. The tie and rail clamp being made of metal, the opposite rails will be electrically connected and though the fish plates might carry some of 25 the current, yet the fish plates alone would not be sufficient. With my construction, however, the rails are very effectively bonded so that the current will always find a path.

Having described my invention, what I 30 claim is:

1. A combined tie and rail bond comprising a metallic tie member having its ends upwardly and inwardly turned to form fixed rail clamps, said tie member being 35 slotted inward of the fixed clamps, the slot having a downwardly and outwardly beveled face and rail clamping members each including a base formed with a slot and each having on its face a downwardly extending lug 40 having a beveled face coacting with the

beveled face of the slot, and a bolt passing through the slot of the rail clamping member and through the tie, said bolt when tightened causing the beveled face of the lug to bear against the beveled face of the 45 slot and force the clamping member downward and toward the rail.

2. A metallic tie member having a rail clamp formed at one end to engage over the base of a rail, said tie member being 50 slotted inward of the clamp, the slot having a downwardly and outwardly beveled face, and a rail clamping member having a base formed with a slot and having on its under- 55 face a downwardly extending lug formed with a beveled face coacting with the beveled face of the slot, and a bolt passing through the slot of the rail clamping member and through the tie, said bolt when tightened causing the beveled face of the lug to bear 60 against the beveled face of the slot and force the clamping member downward and toward the rail.

3. A metallic tie member having a fixed rail engaging clamp at one end, a movable clamp 65 mounted upon the tie member for movement toward or from the rail, a bolt passing through the movable clamp and the tie, the clamp having movement relative to the bolt toward or from the rail, and coacting means 70 on the clamp and on the tie member acting to urge the clamp toward the rail when the bolt is tightened.

In testimony whereof I hereunto affix my signature in the presence of two witnesses. 75

LAFAYETTE B. BAILEY.
